DIGITAL TAPE RECORDER

William R. Guidi, Huntington, N.Y., assignor to Digital
Technology Corporation, Halsite, N.Y.

Filed Oct. 15, 1970, Ser. No. 25,493

Term of patent 14 years

Int. Cl. D14—02

U.S. Cl. D26—14

FIG.1

FIG.2

FIG.3

FIG.4

FIG.5

FIG.6

FIG. 1 is a perspective view of a digital tape recorder showing my new design;

FIG. 2 is a top plan view thereof;

FIG. 3 is a front elevation thereof;

FIG. 4 is a bottom plane view thereof;

FIG. 5 is a rear elevation thereof; and

FIG. 6 is a side elevation, the opposite side being a mirror image of the side shown.

I claim:

The ornamental design for a digital tape recorder, substantially as shown and described.
